UNITED STATES PATENT OFFICE.

JACOB LEPLER, OF PROVIDENCE, RHODE ISLAND.

CLOTHES-PRESSING MACHINE AND THE LIKE.

Application filed November 23, 1927. Serial No. 235,162.

This invention relates to a clothes pressing apparatus and more particularly to the provision of means for condensing exhaust steam used in exerting suction upon the pressing buck and the utilization of the heat evolved during the condensation of the steam to pre-heat water for the boiler.

One object of the present invention is to provide means for condensing the exhaust steam from such apparatus at a point in close proximity to the boiler whereby the trouble and expense incident to the discharge of the steam at a remote point is obviated, and at the same time to utilize the latent heat of the steam to preheat water for the boiler, thus avoiding the trouble and annoyance now occasioned by the free discharge of live steam and effecting a very important saving in the cost of operation.

Another object of the invention is the provision of a compact, self contained apparatus of the character described which may be installed in an office building and operated without annoying the neighboring tenants by reason of the elimination of noise and live steam.

A further object of the invention is the provision of an apparatus of this character which is of simple construction and capable of being easily operated as well as one in which the condensation of the steam and the preheating of the water for the boiler proceed automatically with the operation of the apparatus.

Other objects and advantages of the apparatus relate to various improved details of construction and advantages of operation as will be more fully set forth in the detailed description to follow.

In the drawings:—

Fig. 1 is a diagrammatic layout of the apparatus showing the various parts in connected relation with a steam clothes pressing machine of a conventional type, and,

Fig. 2 is a detail sectional view of a portion of the condenser, taken along the line 2—2 of Fig. 1.

Referring to the drawings, the numeral 1 designates the main frame of the clothes press for supporting the various parts and serving as a housing for a portion of the operating mechanism. A stationary buck 2 is supported by the frame 1 above the table 3, and a movable pressing head or buck 4 is mounted upon a vertically movable rock arm 5 which is hinged upon a portion of the main

supporting frame 1 to swing about an axis parallel with the longitudinal axis of the buck, whereby the pressing head may be brought into engagement with the buck for 60 pressing the clothes or separated therefrom to provide a free space for spreading a garment upon the buck, the pressing head being brought into engagement with the buck 2 by operation of the pedal 5.

The buck 2 and pressing head 4 are each provided with non-communicating chambers serving respectively as heating and distributing chambers which may be arranged in the well-known manner as shown in United 70 States Patent Number 1,326,982, or any other suitable arrangement of the heating and distributing chambers may be employed as circumstances may require or the exigencies of the case render expedient.

The apparatus is provided with the usual steam boiler 6 having a burner 7 for generating steam. A pipe 8 serves to convey live steam from the boiler 6 to the apparatus, and the pipe 8 is provided with a valve 9 for controlling the flow of steam from the boiler. Branch pipes 10 and 11 extend from the pipe 8 to the heating chambers of the pressing head 4 and stationary buck 2 respectively for suitably heating these members. The pipe 85 10 is provided with a swivel joint 12 or other suitable connection to insure access of steam to the heating chamber of the pressing head without interruption by reason of the movement of the pressing head. A connection between the heating and distributing chambers of the pressing head is actuated by the valve 90 lever 13 to permit flow of steam from the pipe 10 to the distributing chamber of the pressing head whereby steam may be passed through 95 the pad 14 covering the lower face of the pressing head to moisten the garment being pressed. A third branch pipe 15 extends from the pipe 8 and is provided with a self-closing valve 16 and a discharge nozzle 17 for applying suction to the distributing 100 chamber of the buck 2 through the connecting pipe 18 whereby suction may be exerted upon the pad 19 covering the buck 2 to withdraw any steam or condensed moisture from the 105 garment and thus hasten the drying of the same. The provision of separate heating and distributing chambers both in the buck and pressing head as above described in which the distributing chambers are provided with 110 openings communicating with the pads 14 and 19 whereby steam may be applied to and

removed from the garment to be pressed are well-known in the art, a conventional arrangement of the same being shown and described in U. S. Patent Number 1,326,982, although various forms and arrangements of these chambers other than those shown in the patent above cited may be readily employed as may be desired. No specific form and arrangement of these chambers has been shown as they form no part of the present invention and are referred to merely for the purpose of illustrating the operation of the usual and conventional type of mechanism in connection with which my improvement is shown and described although my invention is applicable to other forms of pressing machines.

The self-closing valve 16 may be actuated by a pivoted lever 21 from a pedal 22 through a connection 23 when desired, and a cut off valve 24 is provided in the pipe 15 beyond the point where the connecting pipe 18 enters the pipe 15 whereby steam may be admitted to the distributing chamber of the buck 2 either independently of or to supplement the admission of steam to the distributing chamber of the pressing head 4 through first closing the valve 24 by turning the control handle 25 and then actuating the self-closing valve 16 to pass steam from the pipe 15 to the distributing chamber of the buck 2 through the connecting pipe 18.

The condensed moisture from the heating chambers of the buck 2 and pressing head 4 is led back to the boiler 6 through branch pipes 27 and 28 respectively which connect with a main pipe 29 provided with a one way valve 30 adapted to permit the flow of condensed moisture to the boiler while preventing the flow of water from the boiler to the heating chamber, and which has a hand operated valve 31 for entirely cutting off the boiler from the pressing apparatus where desired.

The suction pipe 15 enters a condenser 34 and communicates with a header 35 located in the condenser, and a plurality of coils 36 extend downwardly from the header and through the base 37 of the condenser to discharge condensed steam into a shallow chamber 38 from which the condensed water is conducted by a pipe 39 to a receptacle 40. A vent pipe 41 provides an opening to the atmosphere from the chamber 38 and is of sufficient size to prevent back pressure in the coils 36. While only four cooling coils are shown in the condenser, in order to simplify the construction, a greater number of coils may be employed, it being my purpose to use the greatest practicable number of coils in order to increase the efficiency of the condenser and provide most effective transferance of the heat from the steam to the water which surrounds the coils 36 in the condenser 34.

In addition to the pipe 28 connecting the heating chamber of the pressing head 2 with the main pipe 29 for conveying condensed moisture to the boiler 6, a branch pipe 42 connects the pipe 28 with the suction pipe 15 adjacent to the condenser 34 and the branch pipe 42 is provided with a hand valve 43 which may be opened upon first admitting steam to the heating chamber of the pressing head to vent the air in the heating chamber. A swivel joint 44 is provided in the pipe 28, similar to the swivel joint 12 previously described, which permits passage of steam through the pipe in all positions of the pressing head.

A water inlet pipe 46, provided with a hand valve 47, enters the base 37 of the condenser, which inlet pipe is preferably a part of the city water system and under pressure sufficient to force water into the boiler 6. A pipe 48 connects the top of the condenser 34 with the base of the boiler 6, and is provided with a check valve 49 which permits flow of water through the pipe 48 to the boiler but prevents flow of water therethrough from the boiler towards the condenser. A pump 50 is also provided for drawing water from a receptacle 40 through a pipe 51 and forcing the water through a pipe 52 provided with a one way valve 53, whereby upon opening the hand valve 54 water may be forced from the pump through the pipe 46, the condenser 34 and the pipe 48 to the boiler. By closing the hand valve 54 water from the receptacle may be forced directly into the boiler through the branch pipe 55 by opening the valve 56 therein for the purpose of cleaning the boiler when desired.

In the use of my improved apparatus the steam is first admitted to the heating chambers of the buck sufficiently to bring these members to the desired temperature for operation, the valve 43 being opened if necessary to vent the air therefrom, and then closed to prevent waste of the steam. The valve 9 normally remains open during the operation of the apparatus. When it is desired to moisten the garment to be pressed steam may be forced thereagainst through the pads 14 or 19 by actuation of the valve lever 13, or the valve 16 after closing the valve 24. In drying the garment being pressed the valve 24 is open and valve 16 is opened to produce a flow of steam through the discharge nozzle 17 and thus exert suction through the pipe 18 and pad 19 for removing moisture from the garment being pressed.

The water in the upright condenser 34 serves to condense the waste steam admitted to the header 35 and coils 36 through the pipe 15 and the condensed water passes to the chamber 38 from which it is drained to the receptacle 40 through the pipe 39.

The water at the top of the condenser 34 is most highly heated by the steam entering

through the header 35 and the coils 36, and this preheated water is forced into the boiler 6 by opening the valve 47 so that the pressure in the city water system forces water 5 through the pipe 46 into the base of the condenser and at the same time forces the more highly heated water at the top of the condenser into the boiler through the pipe 48. The same result may be accomplished by 10 closing the valves 47 and 56, opening the valve 54 and operating the pump 50 to draw water from the receptacle 40 and force it through the pipe 46 through the base 37 of the condenser. Either of the above described 15 methods of operation results in forcing the preheated water at the top of the condenser into the boiler thus insuring a constant supply of heated water for the boiler and conserving the latent heat of the exhaust steam 20 as well as avoiding the necessity for exhausting the steam into the open air. While the suction pipe 15 has been shown for the purpose of illustration as so connected as to exert suction only on the lower stationary buck 25 2 a suitable arrangement of piping may be made for exerting suction on either the lower buck 2 or the pressing head 4 or both as may be desired.

A drain tap 58, having a hand valve 59, is 30 provided in the pipe 46 for draining all of the water from the condenser 34 and the pipe 46 by closing the valve 47 and opening the valve 59 whenever it is desired to drain the condenser. This drain tap may also be 35 used to drain the water from the boiler when desired by opening valves 54 and 56 connecting the base of the boiler with the pipe 46.

By supplying cold water to the base of the condenser at suitable intervals and at the 40 same time removing preheated water from the top of the condenser to the boiler, the water admitted to the boiler is always preheated and the water in the base of the condenser is always substantially cool thus insuring 45 efficient and complete condensation of the exhaust steam.

It will be seen that my improved apparatus places no extra burden on the operator as the parts are so connected as to operate automatically upon opening the valve 47 to add water to the boiler when city water under pressure 50 is employed.

It will be seen that my improved apparatus 55 is capable of use in all devices of this character where a boiler is employed and exhaust

steam is developed which ordinarily must be discharged to the atmosphere whether the exhaust steam is utilized in the apparatus for producing suction or for any other purpose and it is adapted for use, not only with 60 clothes pressing apparatus, but with machines for pressing and shaping hats such as are now employed and which utilize steam in the pressing and shaping of the hats.

What I claim is:

1. A clothes pressing apparatus comprising a buck, a pressing head, a boiler, means for supplying steam from the boiler to the buck and pressing head, a steam suction pipe from the boiler connected with the buck, a 70 condenser comprising a water chamber for condensing the steam from the suction pipe and utilizing the heat of condensation for heating water in the water chamber, means connecting the water chamber with the boiler 75 for supplying heated water to the boiler, and means for applying pressure to the water chamber for forcing heated water therefrom to the boiler.

2. In a clothes pressing apparatus comprising a buck and a pressing head, a boiler, means for supplying steam from the boiler to the buck and pressing head, means for utilizing steam from the boiler for exerting suction upon the buck, and means for condensing the steam under atmospheric pressure after its utilization for exerting suction upon the buck and at the same time preheating water for the boiler, and means for forcing the preheated water into the boiler. 80

3. In a clothes pressing apparatus comprising a buck and pressing head, a boiler, means for supplying steam from the boiler to the buck and pressing head, a steam pipe from the boiler connected with the buck for 95 exerting suction upon the buck, a condenser comprising a condenser coil and a water chamber for condensing the steam from the suction pipe and utilizing the heat of condensation for heating water in the water 100 chamber, said condenser coil being open to the atmosphere, means connecting the water chamber with the boiler for supplying heated water to the boiler, and means for applying pressure to the water chamber for forcing 105 heated water therefrom to the boiler.

In testimony whereof I have affixed my signature.

JACOB LEPLER.
